UNITED STATES PATENT OFFICE.

OLE O. GILBERTSON, OF HAYFIELD, MINNESOTA.

EGG-SHIPPING CASE.

1,128,868.

Specification of Letters Patent. Patented Feb. 16, 1915.

Application filed April 9, 1914. Serial No. 830,698.

To all whom it may concern:

Be it known that I, OLE O. GILBERTSON, a citizen of the United States, residing at Hayfield, in the county of Dodge and State 5 of Minnesota, have invented certain new and useful Improvements in Egg-Shipping Cases; and I do hereby declare the following to be a full, clear, and exact description of the invention, such as will enable others 10 skilled in the art to which it appertains to make and use the same.

My invention has for its object to provide an improved egg-shipping case, especially adapted for use in shipping by parcels post; 15 and to such ends, generally stated, the invention consists of the novel construction and arrangement of parts hereinafter described and defined in the claims.

In the accompanying drawings, which 20 illustrate the invention, like characters indicate like parts.

Referring to the drawings: Figure 1 is a perspective view of one corner of the lower section of the improved case; and Fig. 2 is 25 a vertical section taken centrally through the egg-receiving pockets, some parts being broken away.

The numerals 1, 2 and 3 indicate, respectively, the top, bottom and intermediate sections of the shipping case. Each of these 30 sections is made up of a plurality of corrugated multi-ply straw boards, of well-known commercial form, placed one upon the other, with the corrugations in alternate straw 35 boards crossed. These straw boards are secured together, preferably by pasting or gluing one board upon the other. The division between the top and intermediate sections of the shipping case is indicated by 40 the line $x-x$, and the division between the bottom and intermediate sections of the case is indicated by the line $y-y$, as shown in Fig. 2.

Formed in the intermediate case section 45 3 is a plurality of upper and lower axially aligned egg-receiving pockets 4, which coöperate with pockets 5 and 6 formed, respectively, in the top and bottom case sections. The egg-receiving pockets 4, 5 and 6 are 50 formed by punching or cutting out sections of the straw boards. The walls of these pockets are serrated, and the teeth 7, formed thereby, directly engage the eggs Z, and 55 yieldingly hold the same within said pockets. The openings in the straw boards, forming the lower extremities of the egg-receiving

ing pockets, diminish in diameter, so that the eggs are engaged from end to end by the teeth 7. Obviously, the teeth 7 will bend, to permit eggs of different sizes to be placed 60 in the pockets. After the eggs are placed within the pockets, and the case sections assembled, the same are held against sliding movement one upon the other by long wire 65 nails or headed pins 8 passed through alined perforations formed in the sections of the case. The case is then wrapped in a paper 9, and tied with a cord, not shown. It is, of course, understood that the improved 70 egg-shipping case may be made in various dimensions, to receive and carry different numbers of eggs.

What I claim is:—

1. An egg-shipping case made up of sections placed one upon the other, each of said 75 sections comprising a plurality of corrugated multi-ply straw boards placed one upon the other and secured together, and co-operating egg-receiving pockets formed in the inner faces of said sections, the openings 80 in the straw boards, forming the lower extremities of said pockets, diminishing in diameter.

2. An egg-shipping case made up of sections placed one upon the other, each of said 85 sections comprising a plurality of corrugated multi-ply straw boards placed one upon the other and secured together, and co-operating egg-receiving pockets formed in the inner faces of said sections, the openings 90 in the straw boards, forming the lower extremities of said pockets, diminishing in diameter, and the edges of the straw boards, forming the walls of said pockets, being serrated.

3. An egg-shipping case made up of sections placed one upon the other, each of said 95 sections comprising a plurality of corrugated multi-ply straw boards placed one upon the other, with the corrugations of 100 alternate boards crossed, and secured together, and co-operating egg pockets formed in the inner faces of said sections, the inner edges of the straw boards, forming the walls of said pockets, being serrated, and the openings in the straw boards, forming the lower extremities of said pockets, diminishing in diameter.

4. An egg-shipping case made up of sections placed one upon the other, each of said 110 sections comprising a plurality of corrugated multi-ply straw boards placed one

upon the other, with the corrugations of alternate boards crossed, and secured together, coöperating egg pockets formed in the inner faces of said sections, the inner 5 edges of the straw boards, forming the walls of said pockets, being serrated, and the openings in the straw boards, forming the lower extremities of said pockets, diminishing in diameter, and pins holding said sections 10 against sliding movement one upon the other.

5. An egg-shipping case made up of top, bottom and intermediate sections placed one upon the other, each of said sections comprising a plurality of corrugated multi-ply 15 straw boards placed one upon the other, with

the corrugations of alternate boards crossed, and secured together, coöperating egg pockets formed in the inner faces of said sections, the inner edges of the straw boards, forming 20 the walls of said pockets, being serrated, and the openings in the straw boards, forming the lower extremities of said pockets, diminishing in diameter, and pins holding said sections against sliding movement one 25 upon the other.

In testimony whereof I affix my signature in presence of two witnesses.

OLE O. GILBERTSON.
